(57) **CLAIM**

I claim the ornamental design for a lighted outlet cover plate, as shown and described.

DESCRIPTION

FIG. 1 is a front perspective view of a lighted outlet cover plate;

FIG. 2 is a rear perspective view of the lighted outlet cover plate of FIG. 1;

FIG. 3 is a front view of the lighted outlet cover plate of FIG. 1;

FIG. 4 is a rear view of the lighted outlet cover plate of FIG. 1;

FIG. 5 is a side view of the lighted outlet cover plate of FIG. 1;

FIG. 6 is a top view of the lighted outlet cover plate of FIG. 1;

FIG. 7 is a bottom view of the lighted outlet cover plate of FIG. 1;

FIG. 8 is a front perspective view of another embodiment of a lighted outlet cover plate;

FIG. 9 is a rear perspective view of the lighted outlet cover plate of FIG. 8;

FIG. 10 is a front view of the lighted outlet cover plate of FIG. 8;

FIG. 11 is a rear view of the lighted outlet cover plate of FIG. 8;

FIG. 12 is a side view of the lighted outlet cover plate of FIG. 8;

FIG. 13 is a top view of the lighted outlet cover plate of FIG. 8; and,

FIG. 14 is a bottom view of the lighted outlet cover plate of FIG. 8.

The broken lines present in the figures are included for the purpose of illustrating portions of the article which form no part of the claimed design.
